UNITED STATES PATENT OFFICE.

EDWARD A. DUBÉY, OF BROOKLYN, NEW YORK, ASSIGNOR OF ONE-HALF
TO JAMES LANGAN, OF SAME PLACE.

ENVELOPE.

SPECIFICATION forming part of Letters Patent No. 448,611, dated December 30, 1890.

Application filed December 16, 1889. Serial No. 333,849. (No model.)

To all whom it may concern:

Be it known that I, EDWARD A. DUBÉY, of Brooklyn, county of Kings, State of New York, have invented certain new and useful 5 Improvements in Envelopes, of which the following is a specification.

My invention relates to envelopes so constructed as to render clandestine opening impossible; and it consists in certain details of 10 improvement and in combination of parts, which will be more fully set forth in the subsequent specification, reference being had to the accompanying drawings, forming part thereof, wherein—

15 Figure 1 represents the envelope-blank spread open. Fig. 2 represents a back view of my improved envelope, the tongue D being shown turned down. Fig. 3 represents a back view of my envelope sealed.

20 My blank is cut in shape of an ordinary envelope-blank, with the addition of the tongue D to the lower flap C. This tongue D has a series of fine perforations h, of any convenient shape, the perforations being placed in 25 close proximity to one another, some being narrow parallel slits running vertically or in any other direction, some star-shaped openings; but any other suitable shape may be imparted to these closely-placed perforations.

30 This tongue D is intended to be folded down against the inner side of the bottom flap C. Out of the bottom flap C, I form by a substantially V-shaped incision another tongue i, which is so situated that the perforated 35 part of the tongue D will lie behind it when the envelope is formed. Any number of similar incisions and tongues i may be so constructed as to fold upon the upper flap E. This tongue i is surrounded by slits and perforations k k', that are also placed close together to weaken the paper between them, and that are so arranged that when the bottom flap C is folded upon the side flaps A and B they will be in position to be covered by the

40 top or seal flap E. The side flaps A B also have slits and perforations j j', of any convenient shape, placed close together to weaken the paper between them, and so located that they will finally be covered by the seal-flap 45 E. The seal-flap E is cut vertically at the points l l', so that when folded down the lip

m, having perforations and slits p between the slits l l', is pasted on the perforated part h of the tongue D, and finally the tongue i is pasted upon the lip m and slits l l', thus forming a double seal. The upper flap E is covered along its inner face with adhesive substance, which when folded will fall exactly on the perforations and slits k k' and j j'. The perforations k k', j j', and h are so arranged 55 that when the upper flap E is sealed upon them it takes sufficient hold to keep the envelope closed, and yet these slits and perforations are so narrow and small that none of the adhesive substance is forced through into 60 the inclosed matter. When this envelope is opened clandestinely the fact is easily detected, as the numerous points and narrow pieces of paper presented for contact with the adhesive substance will hold some particles 65 of such substance, and as they are so weak that some of them will necessarily be ruptured in opening, and when the envelope has been 70 clandestinely opened by means of steam or otherwise and is again sealed the adhesive 75 substance will now enter the larger openings formed by the tearing, and will cause the letter to be gummed fast to the envelope, thus proving the fact that the package has been 80 tampered with.

The slits n n' and o o' are employed for the detection of the introduction of any sharp instrument, for when gummed fast to the seal-flap E the instrument will pass into the slit o' or n, and the space between n n' o o' being fast at all intermediate points will be torn out by forcing the instrument in any direction, as the paper in these spaces is weakened by the slits and perforations j j'. Therefore,

Having fully described my invention, what 90 I claim, and for which I pray Letters Patent, is—

1. In an envelope, the lower flap C, provided with the outwardly-projecting tongue D and with the inner tongue i, projecting in 95 the same direction as the tongue D and adapted to be folded over the upper flap, substantially as specified.

2. In an envelope, the tongue i, cut substantially V-shaped from the body of the lower 100 flap C, in combination with the lip m, having perforations and slits p between the slits l l',

cut in the upper or seal flap E, substantially for the purposes specified.

3. An envelope having the upper or seal flap E, bearing the lip *m*, having perforations 5 and slits *p* between the slits *l l'*, the side flaps A and B, bearing the slits and perforations *j j'* and the slits *n n' o o'*, the bottom flap C, having the tongue D, bearing slits and perforations *h*, turned down behind said flap C,

and the tongue *i*, cut substantially V shape 10 from the body of the lower flap C, the perforations and slits *h* falling on the incision of the tongue *i*, substantially as described.

EDWARD A. DUBÉY.
